[57] CLAIM

The ornamental design for a combined apron and gown, as shown and described.

DESCRIPTION

FIG. 1 is a front elevational view of a combined apron and gown showing my new design;

FIG. 2 is a rear elevational view of the design as shown in FIG. 1;

FIG. 3 is a slightly enlarged plan view of the front of the design, shown in an unfolded pre-use mode; and,

FIG. 4 is a slightly enlarged plan view of the reverse or rear side of the design as shown in FIG. 3 in such unfolded pre-use mode.

Fig. 2.
